SIEGMUND LOEWE, OF BERLIN-FRIEDENAU, GERMANY, ASSIGNOR TO RADIO CORPORATION OF AMERICA, A CORPORATION OF DELAWARE

TUNED RECEIVER TUBE

Application filed October 25, 1926, Serial No. 143,889, and in Germany November 4, 1925.

It has recently been suggested in the radio art to enclose in receiver tubes a part of the other circuit elements such as coils, high-ohmic resistances, and coupling condenser. 5 However, one essential feature of the problem to be solved in this connection remained unsolved in so far as no ways and means have been known to mount tuned elements in the tube in such a manner that the tube would 10 handle only a very definite frequency, while remaining inoperative or opaque in the case of other frequencies.

It is an object of this invention to provide a vacuum tube which is highly selective. 15 It is a further object of this invention to provide a space current device which will be responsive only to a definite frequency.

The manner of carrying out this invention will be readily apparent from the following 20 description taken in connection with the accompanying drawing in which:

Figure 1 is a diagrammatic view of a device embodying the invention.

Figures 2, 3, 4, and 5 are modifications of 25 the device shown in Figure 1.

In Figure 1 is shown a vacuum tube comprising a hot cathode 1, grid 2 and plate or anode 9. Inside this vacuum tube, to be more precise, between the cathode and the 30 grid, or as shown in Figure 3 between grid and plate, there is mounted a means adapted to produce or allow of the selection of a definite frequency. The said means of Figure 1 consists of a piece of quartz crystal 3 or 35 other piezo-electric material which is carried by a support 4 preferably made of metal and connected with the cathode. In Fig. 4 the crystal support is shown connected to the anode. The piezo-electric excitation of the 40 said quartz crystal is effected by the alternating current potentials that are fed in or which are generated inside the tube, said potentials being of a frequency to which the said quartz crystal is tuned. For excitation 45 purposes, part of the grid circuit is formed plate-fashion as indicated at 5, so that the quartz crystal comes to be located inside an electrical field. Now, if between the terminals 6 and 7, alternating current potentials 50 are supplied, the grid 2 becomes subject to

a marked supplementary excitation provided the incoming wave is exactly equal to the natural period or to a harmonic of the quartz crystal. The arrangement may be modified in a way as indicated in Figure 2. The grid 55 lead 6 is brought inside the tube to a free-ended electrode which is mounted opposite the quartz crystal 3. The grid itself is united with a point on the surface of the said quartz crystal, for instance, by a wire 8 brought 60 close to said surface. In the presence of resonance of the quartz crystal, it receives strong charges whereby the flow of electrons across the tube to the plate 9 is controlled. In this manner, very strong periodic alternating 65 current potentials having the period of the quartz crystal are obtained at the consuming or working device 10, which may be connected, for example, between plate and cathode by way of battery 11. The action 70 upon the mean direct current value in the circuit 10, 11, can be increased by that a stopper condenser 12 is united with the grid which is shunted by a high-ohmic resistance 75 13. This results in the well known audio effect, so that the grid which is rendered markedly positive by virtue of the piezo-electric potentials, receives charges from the filament which gradually make the grid potentials negative whereby a strong alteration 80 of the plate current is occasioned. Parts 12 and 13 may be built directly into the tube.

In Figure 3 another embodiment of the idea underlying the invention is illustrated. In this case, the grid is built in the usual manner, but the plate 9 bears a quartz crystal 14 in such a way that the same is capable of free oscillations, with its piezo-electric potentials becoming thus added to the plate potentials. The plate or anode embraces or 90 envelops the surface of the quartz crystal turned towards the filament in the form of spangle- or buckle-shaped pieces 15. Now, if the incoming wave is equal to the frequency of resonance of the quartz crystal, the piezo-electric potential becomes added to the potential of the plate. In the presence of resonance, and if the plate potential is set to a convenient constant value, there occurs a marked variation of the plate current; and 100

- in conformity with well known rules for thermionic tubes arrangements can be so made that the positive piezo-electric potentials result in a substantial increase in the 5 plate current, whereas the negative potentials occasion no decrease of the same. In the presence of other adjustments, the mean value of the plate current undergoes no alterations, but then a substantially amplified 10 alternating current component arises in the plate current; but this happens only if the exciting frequency is equal to the period of oscillation of the quartz crystal or one of its overtones.
- 15 Of particular value and importance is the further development of the scheme as illustrated in Figure 4 which is a multiple-unit system built into one tube which is made highly selective for definite frequencies cor- 20 responding to the particular period of the quartz crystal possessing piezo-electric properties and which is mounted inside the said tube. While in the case of Figure 4 another disposition of the quartz crystal is shown, it 25 is evident that also one of the schemes illustrated in Figures 1 to 3 may be used with the same end in view.

Within a single vacuum vessel 16 is sealed the said multiple-unit system comprising 30 cathodes 17, 18, (preferably connected in series), the grids 19, 20, the plates or anodes 21, 22, the stopper condenser 23, and the leak resistance 24. As coupling means between both 35 systems is used the piezo-electric quartz crystal 25 which may be excited, for instance, by the electrodes 26. The lead-ins or seals are denoted by 27, 28, 29 and 30, and these are brought to the first grid, the heating filaments, and the first and second plates, 40 respectively. The plate lead of the first plate may contain the high-ohmic resistance 31, and also this resistance may be confined within the tube. But in its stead, also an impedance, e. g., a choke coil, or the high- 45 ohmic direct current resistance 31 can be provided outside the tube as shown in Figure 5. When the grid 19 is excited by an alternating current potential, there is set up a marked potential at the electrodes 26, by virtue of 50 piezo-electric excitation whenever the incoming wave is tuned to the periods of oscillation of the quartz crystal. These potentials occasion a charge across the coupler condenser 23, and control action by the grid 20, 55 whereby corresponding control of the plate current in the second system is occasioned. Contradistinct from known resistance-coupled multiple-unit systems, there is here obtained an extremely sharp selectance by the 60 tube itself.

Selectively acting thermionic tubes of the type hereinbefore disclosed have a very wide practical application not only in radio telegraphy arts, but also in other electrotechnical fields.

Having thus described my invention, I claim:

1. A vacuum tube having three electrodes and a piezo-electric control element mounted therein, said element being coupled to two of said electrodes and being responsive to only a predetermined frequency. 70

2. A vacuum tube having filament, grid and plate elements mounted therein a piezo-electric device mounted within said tube, said piezo-electric device having a natural period of mechanical vibration, and leads connecting said device to said grid and one of said other elements, said piezo-electric device cooperating with the said elements and the said leads to form an alternating current circuit whose period is governed by said device. 75

3. A vacuum tube having filament, grid and plate elements mounted therein, a piezo-electric device mounted within said tube, said piezo-electric device having a natural period of mechanical vibration and coupled directly to said grid and one of said other elements, said piezo-electric device forming with said electrodes to which it is connected an alternating current circuit which determines the frequency at which said tube operates. 80

4. A vacuum tube having filament, grid and plate electrodes, and a frequency determining means, all completely mounted within said tube, said means comprising a piezo-electric body having a natural period of mechanical vibration, and means coupling said body to two of said electrodes. 85

5. A vacuum tube having filament, grid and plate elements, and a frequency determining means, all completely mounted within said tube, said means comprising a piezo-electric body having a natural period of mechanical vibration, and means connecting said body to said grid and said filament. 90

6. A vacuum tube having filament, grid and plate elements, and a frequency determining means, all completely mounted within said tube, said means comprising a piezo-electric body having a natural period of mechanical vibration, and means coupling said body to said plate and said filament. 95

7. A multi-stage vacuum tube each stage 100 of which has a filament, grid and plate electrode, all of which electrodes are included within said tube, in combination with means to couple said stages together, and a piezo-electric means coupled to electrodes within said tube, serving as a frequency determining element for said stages, both said last mentioned means being included within said tube. 105
